Primary Examiner — Jonathan J Han*Assistant Examiner* — Amanda J Berlinski(57) **CLAIM**

The ornamental design for an oral screening device, as shown and described.

DESCRIPTION

FIG. 1 is a top perspective view of an oral screening device in accordance with our design;

FIG. 2 is a front elevational view of the oral screening device in accordance with FIG. 1;

FIG. 3 is a first side elevational view of the oral screening device in accordance with FIG. 1;

FIG. 4 is a back elevational view of the oral screening device in accordance with FIG. 1;

FIG. 5 is a second side elevational view of the oral screening device in accordance with FIG. 1

FIG. 6 is a top end view of the oral screening device in accordance with FIG. 1; and,

FIG. 7 is a bottom end view of the oral screening device in accordance with FIG. 1.

The dash-dot-dash broken lines in the drawings define the bounds of the claimed design and form no part thereof.
